UNITED STATES PATENT OFFICE.

JOEL C. KERSTETER, OF MINNEAPOLIS, MINNESOTA, ASSIGNOR TO ELECTRIC HEAT REGULATOR COMPANY, OF MINNEAPOLIS, MINNESOTA, A CORPORATION OF MINNESOTA.

THERMOSTAT FOR ELECTRIC HEAT-REGULATING SYSTEMS

1,020,289.

Specification of Letters Patent.

Patented Mar. 12, 1912.

Application filed May 25, 1911. Serial No. 629,367.

To all whom it may concern:

Be it known that I, JOEL C. KERSTETER, of Minneapolis, Hennepin county, Minnesota, have invented certain new and useful Improvements in Thermostats for Electric Heat-Regulating Systems, of which the following is a specification:

My invention relates particularly to the timing devices for thermostats by means of which the thermostat may be automatically switched, generally from a low to a higher temperature during the early morning hours to open the drafts and start the fire.

The primary object of my present invention is to provide an improved means for mounting the clock attachment or timer to the end that it is readily accessible for winding and setting purposes.

A further object is to provide a supporting means for the clock, which will be simple and inexpensive in construction and neat and ornamental in appearance.

My invention consists generally in pivoting the timer on the front of the thermostat to allow its position to be reversed and expose the winding and setting mechanism.

In the accompanying drawings forming part of this specification, Figure 1 is a front view of a thermostat with my invention applied thereto, Fig. 2 is a side view of the lower portion of the thermostat, Fig. 3 is a detail view of the clock supporting device removed from the thermostat.

In the drawing, 2 represents the thermostat proper, having an adjusting mechanism 3 by means of which the relative position of the thermostat bar and the contact points is changed to effect a closing of the circuit at a predetermined temperature, and a shifting of the dampers of the heating apparatus.

Clock devices have been mounted on thermostats for automatically shifting the adjusting mechanism at a predetermined time, but it has either been necessary to remove the clock entirely from the thermostat for winding or setting purposes or else it has been mounted in such a manner on the thermostat that access to the winding and setting devices is necessarily awkward and inconvenient. To obviate this objection I provide a plate 5 secured to the thermostat base by any suitable means and having outwardly turned arms or standards 6 and 7,

Pivot pins or screws 8 are mounted in these arms and engage a clock 9 of the circular type, preferably such as is usually used for thermostatic timers. The arms 6 and 7 are sufficiently flexible to allow the removal of the clock from its attachment to the thermostat without adjusting the screw pivots 8. A sliding pin 10 is mounted in one of said arms in position to contact with the wall of the clock and is yieldingly held by a spring 11. The inner end of the pin is preferably rounded as shown in Fig. 2, and is adapted to slip into a recess or depression 10' provided in the wall of the clock being yieldingly held therein by the spring 11. The clock is thus held securely against premature tilting, but when grasped by the hand can be easily pressed to the right or the left to disengage the pin from its seat and swing the clock on its pivots until the back is exposed and accessible.

An arm 12, connected with the alarm mechanism, has an antifriction roller 13 in position to engage a lever 14 that is pivoted at 15 on the plate 5 and is connected with a bar 16 through which the adjusting mechanism of the thermostat, not shown, is controlled. The release of the arm 12 when the alarm is set off will cause the movement of the arm into engagement with the lever 14, oscillating it and operating the bar 16 to shift the adjusting mechanism. The clock swings easily on its pivot either to the right or to the left and a slight pressure on one side will serve to disengage it from the pin 10 and allow it to swing on its pivots until the back of the clock is exposed to view, and where its winding and setting mechanism can be easily reached and manipulated. It is not necessary to remove the clock and there is, therefore, no danger of dropping and breaking it and there are no swinging parts which might catch on the clothing and be broken or torn off. The application to a thermostat already installed can be easily performed and the extreme simplicity of the device, involving, as it does, but few parts of simple construction, insures the operativeness of the attachment at all times and renders uncertainty of operation practically impossible.

I claim as my invention:

1. The combination with a thermostat and its adjusting mechanism, of a timer, mecha-

nism actuated by the timer for shifting said adjusting mechanism, and means for pivotally supporting the timer at points adjacent the front face thereof, and in a plane passing centrally through the timer.

2. The combination with a thermostat and its adjusting mechanism, of a timer, mechanism actuated by the timer for shifting said adjusting mechanism, and means for pivotally supporting the timer at points adjacent

the front face thereof, and in a plane passing centrally through the timer, and a yielding catch for locking said timer in normal position.

In witness whereof, I have hereunto set my hand this 22d day of May 1911.

JOEL C. KERSTETER.
